W. OLIVER,
COTTER AND THE LIKE,
FILED JULY 29, 1922.

Inventor.
W^m. Oliver.

James R. Keast
ATTORNEY

UNITED STATES PATENT OFFICE.

WILLIAM OLIVER, OF MONTREAL, QUEBEC, CANADA.

COTTER AND THE LIKE.

Application filed July 29, 1922. Serial No. 578,525.

To all whom it may concern:

Be it known that I, WILLIAM OLIVER, of the city of Montreal, Province of Quebec, Dominion of Canada, a subject of the King of Great Britain, have invented certain new and useful Improvements in Cotters and the like; and I do hereby declare that the following is a full, clear, and exact description thereof.

10 The object of the present invention is to provide a cotter for general use which will take the place of "split cotters" heretofore in common use and with which so much trouble has been experienced.

15 In locomotive construction particularly in the smoke-box when split cotters of the larger sizes are employed it has been in most instances impossible to remove the cotters unless the split end was first sheared off 20 with a chisel as the split portions when spread become distorted and will not go through the slot in the cotter pin or stud. Furthermore the cotters frequently become "frozen" owing to the intense heat of the 25 smoke box which of course adds to the difficulty of removal.

My improved cotter is designed to overcome these difficulties. It can be readily inserted and withdrawn and even if it becomes "frozen" the leverage provided by its 30 peculiar construction enables it to be easily set free and withdrawn without injury to it.

The use of this cotter is widespread as it may be employed with equally advantageous 35 results in all classes of machinery and rolling stock.

Other advantageous features are that it is positively locked against displacement when in use and as it places its cotter pin or stud 40 under tension and bears tightly against the member being held play which might occur with the ordinary split cotter is eliminated.

For full comprehension however of my invention reference must be had to the accompanying drawings in which similar reference characters indicate the same parts, and wherein:

Figure 1 is a part elevation and part sectional view illustrating my improved cotter 50 in use;

Figure 2 is a plan view thereof;

Figure 3 is an end elevation located at the forked end of the cotter;

Figure 4 is a detail view of an intermediate prong; and

Figure 5 is a similar view of one of the flanking prongs.

The accompanying drawings illustrate the preferred embodiment of the invention.

This embodiment is of substantially trident form, the three prongs constituting the forked end being indicated at 2, 3 and 4 and terminating in a shank 5. The middle prong 3 hereinafter referred to as the tongue of the cotter is adapted to be inserted 60 through the slot 6 in the cotter pin or stud 7 and the two flanking prongs 2 and 4 which I prefer to term jaws are adapted to embrace or straddle the exterior of the latter. The tongue and jaws are constructed separately and their portions which form the shank 5 are welded or riveted as at 8. The tongue 3 is straight in plan view and in side elevation is tapered and curved laterally in hooked-form presenting cam faces 9 and 10 65 through the former being adapted to bear against the plate 12 or other object being secured and the latter against the side 13 of the slot farthest therefrom.

The jaws 2 and 4 are bowed outwardly in 70 plan view as at 15 to conform to the exterior of the pin or stud and their free ends which approach the tongue sufficiently to provide a restricted mouth 16 are turned out sharply as at 17 to facilitate the entry of the stud 75 to position between the jaws. The latter are curved laterally as at 18 in a manner similar to the tongue and their cam faces 19 coincide with the cam face 9 on the latter so that all three faces bear together upon 80 the plate 12.

The manner in which a cotter thus constructed is inserted and withdrawn is as follows:

Assuming the pin or stud is in position 95 the tongue of the cotter is inserted through the slot with the cotter held in the position indicated in dotted lines in Figure 1. The inserting movement is continued until the inserting movement is continued until the cam face 10 of the tongue is bearing against 100 the side 13 of the slot and all three cam faces 9 and 19 are bearing against the plate 12. The shank 5 is then swung towards the latter until it is substantially perpendicular to the axis of the stud. During this movement the jaws are sprung over the latter 105

and the hooked ends caused to assume positions substantially parallel to the axis of the stud, the leverage produced enabling the cotter to be thus positioned with ease and at the same time placing the cotter pin under tension and preventing play of the pin or of the plate 12.

The withdrawal of the cotter is accomplished by reversing the inserting operation.

10. It may be found desirable to temper the cotters which are employed in locomotive smoke-boxes owing to the intense heat to which they are subjected. This may be done by heating the forked end of the cotter to a blood red approximately 700° F. and then dipping same in oil.

15. In order to start the cotter when withdrawing one which is "frozen" the end of the shank 5 is sheared off as at 20 to enable 20 a chisel to be inserted beneath it as indicated in Figure 1 in dotted lines.

25. What I claim is as follows:

1. A comparatively inflexible cotter constructed and arranged to be inserted or withdrawn by movement in an arc coincident with its length.

2. A comparatively inflexible cotter having a forked end and constructed and arranged to fulcrum thereon when being inserted or withdrawn.

3. A comparatively inflexible cotter having a forked end and the prongs of the fork being curved laterally in the same direction and presenting coincident cam faces.

35. 4. A comparatively inflexible cotter for retaining a pin or the like in place consisting of a member of substantially trident form the prongs of the fork being curved laterally.

40. 5. A comparatively inflexible cotter for re-

taining a pin or the like in place consisting of a member of substantially trident form, the middle prong of which is adapted to be inserted through the pin and the flanking prongs adapted to straddle and grip the pin the prongs being curved laterally in the same direction and presenting coincident cam faces.

6. A comparatively inflexible cotter for retaining a pin or the like in place consisting of a member of trident form the middle prong being tapered and adapted to be inserted through the pin and the flanking prongs being adapted to straddle and grip the pin, all of said prongs being curved laterally in the same direction in hooked form.

7. A comparatively inflexible cotter having a forked end and constructed and arranged to fulcrum thereon when being inserted or withdrawn, the opposite end presenting an angular face against which a tool may be positioned for the purpose of "starting" the cotter.

8. A comparatively inflexible cotter of 65 trident form the middle prong of the fork being straight in plan view and curved laterally in hooked form in side elevation and the flanking prongs being bowed outwardly relatively to the middle prong in plan view 70 and curved laterally in hooked form in side elevation in a curve coincident with the lateral curve of the middle prong.

In testimony whereof I have signed my name to this specification in the presence of 75 two witnesses.

WILLIAM OLIVER.
